(57) **CLAIM**

The ornamental design for a recessed downlight for indoor use, as shown and described.

DESCRIPTION

FIG. 1 is a front perspective view of the recessed downlight for indoor use of the present invention showing my new design, with the dotted lines forming no part of the claimed design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a top plan view thereof.
